(57) **CLAIM**

We claim the ornamental design for endoscope immersion tray, as shown.

DESCRIPTION

FIG. 1 is a perspective view of an endoscope immersion tray according to the present invention as seen from the top, front and right sides;

FIG. 2 is a top plan view thereof;

FIG. 3 is front elevational view thereof;

FIG. 4 is a bottom plan view thereof;

FIG. 5 is a right side elevational view thereof;

FIG. 6 is a left side elevational view thereof; and,

FIG. 7 is an exploded perspective view from the top, front, and right sides.
